A. TRAUBE

CLEANING DEVICE

Filed June 26, 1926

INVENTOR

ABRAHAM TRAUBE

BY

Wallace & Lohman

ATTORNEY

UNITED STATES PATENT OFFICE.

ABRAHAM TRAUBE, OF BROOKLYN, NEW YORK.

CLEANING DEVICE.

Application filed June 26, 1926. Serial No. 118,630.

This invention relates to a new or improved device more particularly intended for use in removing spots, such, for example, as paint spots, from textile articles, such as articles of clothing, and has for its main object to provide a device which will be simple in construction and action, low in cost of manufacture and yet efficient and convenient in operation.

10 The present device is particularly adapted for use in conjunction with the well-known dry-cleaning of articles of clothing; after such dry-cleaning has been effected there frequently remain spots or other marks 15 which must be given special treatment to effect their removal—the present device will be found particularly advantageous for use in such circumstances.

With the above and other objects in view 20 the invention will now be described with reference to the accompanying drawing in which:—

Figure 1 is a longitudinal sectional view through a device constructed according to 25 the present invention, and,

Fig. 2 is an end view thereof.

In the drawings, the numeral 4 indicates a receptacle, which may conveniently be in the form of a cylindrical elongated container, adapted to receive and hold any suitable liquid or mixture possessing cleansing or solvent properties and such, for example, as carbon tetrachloride.

At one end 5, said container is provided 35 with a filling opening or nozzle 6 which can be conveniently closed by a cork 8.

Integral with or affixed to the side wall of the container 4 is a scraper 10 which extends forwardly of the end wall 5 and is 40 preferably curved downwardly or away from said end as shown.

Behind said scraper is disposed one end of a small tube or pipe 12 which extends through the side wall of the receptacle and 45 has its other end controlled by a valve 14, provided with a stem 16 which passes through and beyond a bushing 18 in the end wall 5 and has its extremity provided with a head 20 between which and the bushing 18 is mounted a spring 22 acting to normally 50 keep the inner end of the tube 12 closed.

Attached to or integral with the side wall of the container opposite to that which carries the scraper 10 is a holder 24 adapted to 55 receive a brush 26. The said holder is pref-

erably constructed to permit of the removal of the brush for renewal or other purposes.

When it is desired to use the device, it being assumed that the desired cleanser or solvent has been previously poured into the 60 container, the device is grasped in the hand and the scraper brought to bear on the spot or mark to be removed and at the same time the valve head 20 is depressed by a finger or the thumb to open the valve 14 and permit liquid to flow through the tube 12 on to the spot or mark as may be found necessary to aid in softening the spot or mark and facilitating the scraping operation.

When the above operation has been carried as far as may be judged expedient, the device is turned in the hand and the brush brought into play, the above operations being alternated until the desired effect is obtained.

It should be noted that as the container 4 is air-tight or practically so, only comparatively small quantities of the cleanser or solvent contained therein can be caused to flow from the tube 12 while the scraper 10 is being used. If therefore the container is only partially filled, on the brush 24 being brought into use the necessary reversal of the device in the hand to effect this will free the tube 12 from such cleanser or solvent 80 and sufficient air will then leak in past the valve 14 and permit further liquid to flow from the container on the scraper being again brought into use. It is for this reason that the brush and the scraper and tube 90 are respectively located at diametrically opposite points on the side wall of the receptacle.

In accordance with the provisions of the patent statute, I have described the principle of my invention, together with the apparatus which I now consider to represent the best embodiment thereof, but I desire it understood that my invention is not confined to the particular form of apparatus herein 100 shown and described, the same being merely illustrative, and that the invention can be carried out in other ways without departing from the spirit of my invention, and, therefore, I claim broadly the right to employ 105 all equivalent instrumentalities coming within the scope of the appended claims, and by means of which objects of my invention are attained, and the new results accomplished, as herein set forth, as it is obvious that the 110

particular embodiment herein shown and described is only one that can be employed to attain these objects and accomplish these results.

5 What I claim and desire to secure by Letters Patent is:—

1. A fountain device for use in the dry cleaning of textiles comprising a hollow cylindrical handle adapted for use as a container for the liquid to be used, a scraper blade projecting from the container, said blade being adapted to be applied to a textile to clean the same, an outlet tube communicating with the container and having its discharge opening at the same side of the container as the scraper and located in close proximity to the scraper and so that liquid may be discharged while the scraper is applied to the textile, and means for controlling the flow of the liquid discharged through the tube.

2. A fountain device for use in the dry cleaning of textiles comprising an air-tight cylindrical handle adapted for use as a con-

tainer for the liquid to be used, a scraper integral with the side wall of the container projecting from the container beyond the end thereof, an outlet tube for discharge of the liquid to be used, having its discharge opening adjacent the scraper, and means for controlling the flow of the liquid discharged through the tube.

3. A fountain device for use in the dry cleaning of textiles comprising an air-tight cylindrical handle adapted for use as a container for the liquid to be used, a scraper projecting from the container beyond the end thereof, an outlet tube projecting through the side wall of the container for discharge of the liquid, having its discharge opening adjacent the scraper, and having a bore adapted to deliver only small quantities of the liquid at each discharge, and means for controlling the flow of the liquid discharged through the tube.

In testimony whereof I have signed my name to this specification.

ABRAHAM TRAUBE.
